VENDING MACHINE

Meyer E. Schloff, Chicago, Ill., assignor of one-half to Henry J. Bobbe, Chicago, Ill.

Application July 19, 1941, Serial No. 403,105

6 Claims. (Cl. 312—64)

This invention relates in general to coin-controlled vending machines, and while it has more particular reference to improvements in merchandise issuing apparatus for such machines, it will be apparent that certain features thereof have other and more general valuable application.

A principal object of the present invention is the provision of an improved lightweight rigid and strong base unit for supporting a rotatable multiple magazine turret and for also supporting and enclosing merchandise ejecting apparatus and coin-controlled apparatus operable to condition the ejecting apparatus for operation.

Another important object of this invention is the provision in combination with the merchandise ejecting mechanism of a novel latch device operable to preclude actuation of said ejecting mechanism but settable by a coin-controlled device to permit such actuation.

A further object of the invention is the provision in combination with an ejecting mechanism as aforesaid including a finger advanceable to eject merchandise, of a checking device operable to prevent retraction of the finger until completion of a full ejecting stroke, and a new latch device settable to permit advancement of said finger and including means functioning to maintain the set condition of said latch device during the initial part of said stroke.

The invention further contemplates an improved merchandise ejecting mechanism including a reciprocal ejector carrying thereon a latch member displaceable into a non-effective position to permit advancement of said ejector, and said member carrying a blocking member operable to assume an abutting relation with a complementary part to maintain the latch member in its non-effective position during initial advancement of the ejector but being inoperable to regain the abutting relation pursuant to retraction of the ejector.

A further object of the invention is the provision of a novel mount for the rotary multiple magazine turret and including detent means for yieldingly resisting rotation of the turret from any of several positions in which respective magazines register with a discharge section of the machine.

Still another object of the present invention is the provision of a new and improved locking means for retaining the turret upon the base structure of the machine.

Numerous other objects and advantages of the invention will be apparent as it is better under-

stood from the following description, which, when considered in connection with the accompanying drawings, illustrates a preferred embodiment thereof.

5 On the drawings:

Figure 1 is a front elevational view of a machine embodying the principles of the present invention;

Fig. 2 is a horizontal sectional view taken 10 through the machine substantially upon the line 2—2 in Figure 1;

Fig. 3 is a fragmentary vertical sectional view taken substantially diametrically through a multiple magazine turret constituting a part of the 15 machine, the position of the view being indicated by the line 3—3 in Figure 2;

Fig. 4 is a fragmentary plan view of an upper 20 end portion of said multiple magazine turret, the view being taken upon the line 4—4 in Fig. 3;

Fig. 5 is a horizontal sectional view looking 25 downwardly into the base unit of the machine and illustrating certain of the working parts contained therein, this view being taken as indicated by the line 5—5 in Fig. 1;

Fig. 6 is a side elevational view of a ratchet 30 and pawl mechanism and taken upon the line 6—6 in Fig. 5;

Fig. 7 is a vertical sectional view taken through 35 the base unit substantially upon the line 7—7 in Fig. 5 and illustrating in elevation an improved latch mechanism for releasably locking a merchandise ejector member against operation;

Fig. 8 is a fragmentary view illustrating the 40 latch mechanism of Fig. 7 in the unlatched position and also illustrating a part of a coin-controlled actuator member in position for effecting such unlatching of the latch mechanism;

Fig. 9 is a view like Fig. 8 but illustrating the 45 parts in a more advanced stage of their operating cycle wherein the coin-controlled apparatus is withdrawn from the latch mechanism, leaving the same poised for permitting operation of the merchandise ejector;

Fig. 10 is a view like Fig. 7 but illustrating the 50 parts at an earlier stage in their operating cycle, namely, the stage in which an article of merchandise is being ejected;

Fig. 11 is an elevational view partly in section and taken upon the line 11—11 in Fig. 5 for further 55 illustrating the merchandise ejector member, a mount upon which it is reciprocally disposed and the aforesaid latching mechanism;

Fig. 12 is a vertical sectional view illustrating that part of the apparatus shown in Fig. 11 and taken upon the line 12—12 in that figure;

Fig. 13 is a fragmentary plan view looking upwardly at the line 13—13 in Fig. 11 and illustrating a part of ball-detent mechanism for yieldably resisting rotative displacement of the turret from any one of its selectable positions;

Fig. 14 is a fragmentary sectional view taken on the line 14—14 in Fig. 12 for illustrating the manner in which the ejector member and its carriage are disposed slidably upon the mount therefor;

Fig. 15 is a fragmentary perspective view showing the lower end of one of the magazines of the turret; and

Fig. 16 is a fragmentary horizontal sectional view taken upon the line 16—16 of Fig. 1 and illustrating a coin receiving compartment together with a lockable closure member therefor.

For the purpose of illustrating my present invention I have shown on the drawings a machine in which it is embodied. A base unit for the machine comprises a cylindrical side wall 21, and a bottom wall 22, Figs. 7 and 10, which may have a peripheral flange 23 to facilitate the interfabrication of these parts. Preferably, the walls 21 and 22 are made of sheet metal to minimize weight and production cost.

A standard 24, shown plainly in Figs. 10 and 11, has a base portion 25 secured to the bottom wall 22 by any conventional means such as bolts 26. The bolts 26 may be sufficiently long to also serve as means for securing the machine upon a pedestal or the like, if desired. This standard 24 which supports a multiple magazine turret 27 (to be described in more detail hereinafter) is braced against lateral movement, at a section spaced upwardly from the bottom wall 22, by rail members 28 and 29, Figs. 5 and 7, which are integral with an extension member 31 projecting inwardly of the base from a cover plate 32 for a side wall opening 33 in the side wall 21. The extension 31 is integral with the cover plate 32 as is plainly shown in Figs. 5 and 7. A discharge passage 34 for merchandise dispensed by the machine is formed between an inner wall 35 of the cover plate and a protruded wall 37; see Figs. 7 and 10. An inclined portion 37 of the extension 31 forms a feeding apron for the passage 34 and onto which ejected articles of merchandise drop for sliding into and through the passage 34 onto a delivery tray 38, which may be secured to the base side wall as by means of bolts 39 of which one is shown in Figs. 7 and 10. Bolts 41 in Figs. 1 and 5 are employed for securing the cover plate 32 in closing relation with the side wall opening 33. Machine screws 42 shown principally in dotted outline in Fig. 5 are inserted downwardly respectively through the spaced rail members 28 and 29 of the cover plate extension 31 and turned into threaded recesses therefor in the standard 24. Thus, it will be seen that the cover plate 32 with its extension 31 is enabled to brace the standard 24 and likewise the standard is adapted to support and brace the extension member 31 which carries certain parts of the machine hereinafter described.

A boss 43 is formed integrally with the upper end of the standard 24 and is vertically bored and threaded at 44, as plainly shown in Fig. 12, for receiving the lower and threaded end 45 of a long rod or spindle 46 about which the turret 27 is adapted to rotate.

Said turret 27 is made up of a plurality of vertically disposed chambers or magazines 47, there being six of these magazines in the present structure. Each magazine comprises a generally

channel-shaped sheet metal member providing opposed side walls 48 and an inner wall 49. The upper ends of the inner walls 49 are welded or otherwise suitably secured to respective upwardly turned flanges 51 of a hexagonal end plate 52, as shown in Figs. 2, 3, and 4. The lower end portions of the magazine inner walls 49 are similarly secured to downward turned flange 53 of a bottom plate 54; see Figs. 7 and 10. The outer ends of the side walls 48 are shaped to form channels 55 complementally with opposite vertical edges 56 of side panel members 57, also made of sheet metal and secured to flange portions 58 of the side walls 48 in some such manner as by spot welding. It will be seen, therefore, that the several merchandise magazines 47 are retained in a generally cylindrical assembly by the hexagonal upper and lower end plates 52 and 54 and by the side panel members 57. Slender windows of glass 59 are adapted to be slid downwardly into the sets of opposed channels 55, and when they are thus assembled with the turret, as illustrated in Figs. 1 and 2, their lower ends rest upon the upper face of a ring 61 circumscribing a lower end portion of the turret and in turn resting upon the upper edges of sheet metal guard straps 62, Figs. 7 and 15, which bridge and are respectively carried upon the paired side walls 48 of each magazine. A second ring, 63, also circumscribes the lower portion of the turret and is mounted upon the lower face of the ring 61, the ring 63 having a depending skirt or flange 64 serving as a guard and lending a finished appearance to the machine. As clearly shown in Fig. 15, each of the magazines 27 is provided with a bottom plate 65 with upwardly turned flanges 66 welded or otherwise secured to its associated side walls 48. The lowermost of merchandise articles 67 stacked in each magazine is adapted to rest upon this bottom plate 65. Sufficient space is provided between the lower edge of each strap member 62 and the outer edge of its associated bottom member 65 to permit the passage outwardly therebetween of a single merchandise article. Accidental displacement of an article outwardly between the members 62 and 65 is prevented by a leaf spring member 68 secured to and depending downwardly from each of the members 62.

The upper plate 52 of the turret 27 and the lower plate 54 thereof are provided with central axially aligned openings, as that shown at 69 in Fig. 3 in the plate 52, and to the under side of the bottom plate 54 there is secured a disc member 71 constituting part of a detent device generally designated 72, the disc member 71 also having an opening 73, arranged co-axially with the end plate openings as 69. Said openings as 69 receive and have secured therein a tubular member 74 and this tubular member and the opening 73 in the disc 71 receive respective sections of the upright spindle 46 that is disposed in threaded relation with the recess 44 in the boss 43 as aforesaid (see Fig. 12), when the turret is slid downwardly over the spindle into assembly with the machine. Subsequent to this assembly of the turret with the machine, it is locked in place by a key member 75 having opposed resilient legs 76 contractable into a grove 77 circumscribing an upper end section of the spindle 46.

The detent device 72 comprises, in addition to the disc 71, Figs. 10, 12, and 13, a second disc or plate 70 upon the boss 43. This plate 70 has a central opening for receiving the base of the

spindle 46.

spindle 46 and an eccentrically placed opening 78 which registers with a recess 79 in the boss 43 that serves as a spring chamber for a helical spring 81. The spring 81 comprises part of a sub-assembly also including a steel ball 82 and a sleeve 83 press-fitted into the recess 79 and having a slightly inwardly turned flange 84 about its upper end to permit limited projection of the ball 82 from such end under the influence of the spring 81 when the parts are assembled, as illustrated in Fig. 12.

Six recesses 85 spaced equiangularly about the under face of the plate 71 pertain to the six magazines 47 of the turret 27 and are respectively aligned therewith circumferentially of the turret. These recesses 85 are adapted to receive the protruding part of the ball 82 as they are successively carried into registry therewith during rotation of the turret, wherefor the spring pressed ball will yieldingly resist rotation of the turret from these registering positions. The recess 79 and the ball 82 are disposed upon the forward side of the boss 43 so that upon registry of each recess 85 with the ball 82, the magazine 47 corresponding to said recess 85 will register with the feeding apron 37 and be yieldingly arrested in that position. In the present structure, the turret is supported by the plate 71 fixed upon the turret bottom plate 54 and said plate 71 is journaled upon a shoulder 86 of the spindle 46, as illustrated in Fig. 12. A plurality of knobs 87 are secured to certain of the turret panel members 57 in a position to be conveniently grasped by an operator of the machine to facilitate rotation of the turret for placing the magazine 47 containing the merchandise of his selection in registry with the discharge section of the machine comprising the discharge opening 34 and the feeding apron 37 therefor.

Ordinarily the turret 27 will remain permanently assembled with the machine, the locking key member 75 serving to prevent disassociation of the turret from the base portion of the machine by those without authority. Access to the upper ends of the merchandise magazines 47 is had by removing a cover member 88 having a circumferential flange or skirt 89 projecting marginally downwardly over an upper portion of the turret when said cover member is in place. A key operated locking device generally designated 91 is secured to the cover member 88 at a central opening 92 and this locking device carries upon its inner end an elongated locking bar 93 held non-rotatively to a shaft 94 of the locking device by a screw 95. This bar 93 is adapted to be inserted through a rectangular opening 96 in the bridge 97 of an inverted U-shaped locking bracket 98 which is secured to the turret end plate 52. Outwardly turned feet portions 99, Fig. 2, may be provided upon the lower ends of the vertical legs 101 of the bracket 98 to facilitate attachment thereof to the end plate 52 by some such means as welding or bolts. The locking bar 93 is insertable through the locking bracket opening 96 when this bar is turned with its principal axis in parallelism with the principal axis of said opening 96 and subsequent to such insertion the locking device 91 is manipulatable by a key (not shown) for rotating the stem 94 and the locking bar 93 ninety degrees for placing the bar 70 and the opening 96 in the relation illustrated in Fig. 2 for preventing withdrawal of the bar through the opening and therefore preventing removal of the cover member 88. Rotation of the cover member 88 and consequent rotation of 75

the lock stem 94 and the locking bar 93 to place the latter with its principal axis in parallelism with the principal axis of the opening 96 so that the cover plate could be removed, is prevented by a stud 102, Figs. 2 and 3, having a base portion 103 suitably anchored to the under side of the cover member 88 and which projects downwardly between the opposed walls 48 of adjacent magazines 47.

When the turret 27 is arranged with one of the magazines 47 at the discharge section of the machine, as illustrated in Figs. 7 and 10, and in which position the turret is yieldingly maintained by the detent device 72, the lowermost article 67 in such magazine is ejectable forwardly through the space between the lower edge of the guard strap 62 of this magazine and the forward edge upon the bottom plate 65 thereof. Ejection of the merchandise article is effected by ejector apparatus comprising a finger-like member 104, shown plainly in Figs. 5, 7, 10, 11 and 12.

Said ejector apparatus comprises a carriage in the form of a plate 105 with which the finger 104 is integral and this carriage is reciprocally mounted upon the rail members 28 and 29 for fore and aft movement. Normally, the carriage 105 is maintained in its retracted or back-most reciprocal limit by a contraction spring 106, having opposite of its ends connected respectively with an apertured ear 107 depending from the under forward side of the standard boss 43 and with an apertured section 108 in the forepart of the carriage; see Fig. 12. Forward or ejecting movement of the carriage 105 and its ejector finger 104 is effected by a manually operable pull rod 109 suitably anchored in a boss 111 upon the carriage and projecting slidably through an opening 112 in the cover plate 32. A knob 113 is provided upon the outer end of the pull rod 40 109 to facilitate engagement, as by the fingers of an operator, and when the carriage is pulled forwardly for ejecting an article of merchandise the spring 106 is distended and thus energized for returning the carriage to its back-most reciprocal limit when the knob 113 is released. Forward or ejecting movement of the carriage 105 by unauthorized persons is prevented by latch mechanism comprising a latch member 114 pivoted upon the shank of a headed member 115 anchored to the carriage as by means of screw threads. The pivoted member 114 is provided in its lower edge with a notch 116 which is adapted to register with and hook over a retaining member in the form of a locking stud 117 50 which may be formed integrally with the standard 24, as illustrated in Fig. 5. A spring 118 having its upper end connected with the pivoted latch member 114 at an aperture 119 and its lower end secured by means of a screw 121 to the lower end of a vertical bar 122 secured to the carriage 105 by a screw 123, constantly urges said latch member 114 to pivot clockwise, as viewed in Fig. 7, whereby upon return of the carriage into its retracted or back-most position the notch 60 116 will be caused to receive the stud 117 and thus lock the carriage against forward movement until the latch member 114 has been raised out of this locking relation.

Raising of the locking bar 114 for unlatching the same from the stud 117 is accomplished by actuation of a coin-controlled apparatus 124 which may be of any well-known design and which in the present instance is mounted in a hollow boss 125, Figs. 1 and 5 formed integrally

with the base cover plate 32. This coin-controlled apparatus includes a slide bar 126 which may be depressed manually inwardly subsequent to the deposit of a coin 127 within a recess 128 therefor. Normally the slide bar 126 is maintained in the retracted position illustrated in Fig. 5 by means of a contraction spring 129 of which one end is connected with the bar 126 by means of a screw 131, and of which the opposite end is connected by screw 132 with parts fixed with respect to the cover plate 32. A bracket 133, Fig. 5 and Figs. 7 to 10 inclusive, and provided with an inclined cam portion or member 134, depends from the under side of the slide bar 126 at its inner end to which it is secured by screws 135. Said cam member 134 is alined with a cam follower in the form of a roller 136 pivoted upon the shank of a headed member 137 anchored in the back end of the latch bar 114. Therefore, when the slide bar 126 of the coin-controlled apparatus is pressed inwardly, the cam member 134 connected therewith will be moved backwardly or to the right, as viewed in Fig. 10, into engagement with the roller 136, whereupon this roller will be caused to move upwardly along the cam member 134 into the position illustrated in Fig. 8. Backward movement of the slide bar 126 is limited to the position shown in Fig. 8 by a small stop bracket 128 secured to the locking bar 114 and of which a flange 139 abuts with an edge 141 of a notch in the back end of said slide bar; see Figs. 5 and 8. Upon this counter-clockwise pivotal movement of the locking bar 114, a blocking member 142 pivotally mounted upon the shank of a screw 143 attached to the bar 114 will be permitted to drop by the force of gravity from the pivotal position shown in Fig. 7 to the pivotal position shown in Fig. 8, so that upon subsequent retraction forwardly of the coin-controlled slide bar 126 and the consequent removal of the cam member 134 from engagement with the roller 136 and clockwise movement of the locking bar 114 under the influence of the spring 118, the said blocking member 142 will assume the position illustrated in Fig. 9 with its lower end resting upon the upper generally horizontal face of the stud 117. Thus the blocking member serves to preclude relatching of the latch bar 114 and permits forward ejecting movement of the carriage 105 and its finger 104 while being advanced with said carriage incidental to sliding forwardly over the upper face of said stud 117.

The forward ejecting movement of the carriage 105 is ample to displace the blocking member 142 into some such position as illustrated in Fig. 10, where it is carried out of engagement with the stud 117 to allow the latch bar 114 to drop downwardly against said stud under the influence of the spring 118. Following this forward ejecting movement of the carriage 105 and its ejector finger 104, the pull rod 109 will be released and said carriage will be returned to its rear reciprocal limit by the spring 106. During this return movement of the carriage 105 and the parts attached thereto, the blocking member 142 will abut against the forward edge of the stud 117 which will avert the blocking effect thereof by pivoting it clockwise into the position shown in Fig. 7, so that the latching bar 114 can assume the latching position, also shown in Fig. 7. The apparatus will now be locked as aforesaid to prevent an ejecting operation until a coin is deposited in the recess 128 to enable the slide bar of the coin-controlled apparatus 124 to be pushed inwardly for resetting

the latch mechanism into the position shown in Fig. 9.

I provide upon this machine a checking device to prevent retraction of the ejector carriage 105 and tripping of the blocking member 142 to permit relatching of the locking bar 114 until a full ejecting stroke has been executed. This checking device is clearly illustrated in Fig. 6, although Figs. 5, 11, and 14 should also be examined to ascertain the exact location of this device. The device comprises a plate 144 secured to the left side of the standard 24, as viewed in Figs. 5 and 11, screws 145 being used to effect the attachment. A series of ratchet teeth 146 upon the upper edge of the plate 144 are adapted to cooperate with the pointed end of pawl 147 pivotally mounted upon the shank of a screw 148 which is anchored in a side of the ejector carriage 105. A small bracket 149 is also attached to the carriage 105 and supports the upper end of a spring 151 of which the lower end is connected to the upper end of the pawl 147.

In Fig. 6 the carriage 105 is shown in its back or retracted position, wherein the pawl 147 is disposed backwardly of the ratchet teeth 146. When the carriage 105 is pulled forwardly pursuant to an ejecting operation, the point of the pawl member 147 will be caused to successively engage the teeth 146 with a ratcheting action while occupying a zone displaced clockwise about the screw mounting 148 from the position shown in Fig. 6, and while distending the spring 151. Should the pull rod 109 be released while the cam 141 is engaged with the plate 144 at a point between any of the teeth 146, the spring 106 will be unable to function for returning the carriage 105 to the starting or retracted position since the distance between the point of the pawl and its pivotal axis in the screw 148 is greater than the perpendicular or vertical distance between such axis and any of the grooves between the teeth 146. The carriage 105 cannot be raised to enable the pawl 147 to slip backwardly over the teeth 146 under the just described conditions since the carriage has longitudinal grooves as 149, Fig. 14, which receive the slide rail members 28 and 29. Therefore, should an operator, after having deposited a coin in the machine and cocked the latching bar 114 as illustrated in Fig. 9 and after having advanced the carriage 105 part way by pulling upon the rod 109, accidentally lose his hold upon the knob 113, the carriage would be withheld by the checking device from returning to the locked position shown in Fig. 10. Incident, however, to advancing the carriage 105 through a full ejecting stroke, the pawl 147 will be run completely through the row of ratchet teeth 146, whereupon said pawl will be pivoted counter-clockwise by the spring 151 into the position shown in Fig. 6, thus conditioning it for ratcheting freely over the teeth 146 upon return of the carriage to the starting position.

In the operation of the machine, one approaching it for service will first select the variety of merchandise desired by viewing it through its respectively associated window 59 and by grasping one of the turret knobs 87 for rotating the turret to place this window at the front of the machine and consequently the associated magazine 47 in registry with the discharge section of the machine. Thereupon a coin of the required denomination will be deposited in the recess 128 of the coin-controlled device 124 to enable the customer to press the slide bar 126 inwardly. At this time the parts of the machine will be positioned as il-

lustrated in Fig. 7, but as the slide bar 126 is pressed inwardly the cam member 134 carried by this slide bar will engage the roller 136 for causing such roller to be displaced upwardly in the manner shown in Fig. 8 for pivoting the latch bar 114 counter-clockwise and permitting the blocking member 142 to drop into the vertical position, also shown in Fig. 8. After having pushed the slide bar 126 inwardly to the limit, determined by engagement of the part 141 of this bar with the flange of the bracket 138 upon the latching bar 114, the customer or operator will release the slide bar 126, which then withdraws forwardly under the influence of the spring 129 from the roller 136 to permit the latch bar 114 to drop into the position shown in Fig. 9 where it is maintained out of latching relation with the stud 117 by the blocking member 142.

Thereafter the customer will grasp the operating knob 113 for pulling the rod 109 and the carriage 105 with its ejecting finger 104 forwardly incident to projecting said finger against the inner end of the merchandise article at the bottom of the magazine stationed in registry with the discharge section of the machine. During advancement of the carriage, the finger 104 will enter the bottom portion of the registered magazine incident to pushing the article of merchandise 67 forwardly, as shown in Fig. 10, and eventually causing such merchandise article to drop onto the feeding apron 37 from which it slides into the discharge passage 34 and ultimately issues from the machine as it lands in the tray 38 where it is accessible to the customer. Pursuant to this advancement of the ejector carriage the checking device consisting of the ratchet plate 144 and the pawl 147 are conditioned as aforesaid to operate if necessary for preventing return of the carriage until the latter has been advanced sufficiently far for ejecting the merchandise article. After the merchandise article appears upon the tray 38, the operator will release the knob 113 to permit the spring 106 to return the carriage 105 and the parts carried thereby to the starting position, shown in Fig. 7, and incident to this retracting movement of the carriage the blocking member 142 will engage the front side of the boss 117 for pivoting said blocking member clockwise from the position shown in Fig. 10 to the position shown in Fig. 7, thus preventing this blocking member from assuming the position of Fig. 9 and permitting the latching bar 114 to place its notch 116 in latching relation with the stud 117.

Coins deposited in the coin-controlled apparatus are discharged thereby into a base compartment having a vertical side wall 155 and a bottom wall consisting of a plate-like member 156 curved upwardly from a point adjacently to its back edge 157; see Figs. 5 and 16. An access opening 158 (provided in the base side wall 21) for this compartment is closable by a removable plate 159, Figs. 1 and 16. One vertical edge of the closure plate 159 carries a locking strip 161 engageable with an inner marginal portion of the wall 21 about the opening 158 and thus cooperable with a key-actuated locking device 162 and a flanged member 163 for holding said closure plate in closing position. Removal of the closure plate outwardly of the machine base to provide access to the coin receiving compartment is possible when the device 162 is unlocked to carry an arm 164 thereof out of registry with said flanged member 163.

Features of particular advantage in the pres-

ent machine are its unique simplicity in structural design and its adaptability for ease in assembly and disassembly for repair or other servicing. Prior to attaching the standard 24 to the base wall 22 the ratchet plate 144 may be assembled with this standard. Likewise, the various parts attached to and supported upon the cover plate extension 31 may be associated therewith, while complete access is had thereto, to form a sub-structure insertable as a unit through the side wall opening 33, concurrently with placing the cover plate 32 in closing relation with said side wall opening. Normally the pull rod 109 and the coin-controlled apparatus 124, will also be mounted in the cover plate 32 before the latter is disposed upon the base side wall. It will be seen, therefore, that in servicing the machine substantially the entire group of working parts are removable with the cover plate, subsequent to unhooking the spring 106 and to removing the screws 42, Fig. 5, for greatly improving accessibility.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a vending machine having a hollow base unit having a side wall opening, a superposed compartment for articles to be dispensed by the machine, and a standard mounted upright in said base unit to provide support for said compartment; a unitary sub-structure comprising a cover plate for said side wall opening and having an article discharge passage communicating with the interior of said base unit through said side wall opening when the cover plate is in closing relation with said opening, and extension means upon the inner side of said plate for connection with said standard to brace the same, a portion of said extension means being in the form of a feeding apron sloping downwardly communicatively with said passage.
2. In a vending machine having a hollow base unit having a side wall opening, a superposed compartment for articles to be dispensed by the machine, and a standard mounted upright in said base unit to provide support for said compartment; a unitary sub-structure comprising a cover plate for said side wall opening and having an article discharge passage communicating with the interior of said base unit through said side wall opening when the cover plate is in closing relation with said opening, article ejector support means upon the inner side of said plate, said support means being connectible with said standard for bracing both said support means and said standard when the cover member is in closing relation.
3. In a vending machine having a hollow base unit having a side wall opening, a superposed compartment for articles to be dispensed by the machine, and a standard mounted upright in said base unit to provide support for said compartment; a unitary sub-structure comprising a cover plate for said side wall opening and having an article discharge passage communicating with the interior of said base unit through said side wall opening when the cover plate is in closing relation with said opening, article ejector sup-

port means upon the inner side of said cover plate and projecting inwardly of the base unit for connection with the standard for mutual bracing of said standard and said support means when the cover member is in closing relation with said opening, article ejecting means mounted upon said support means for displacement toward the cover plate to execute an article ejection stroke, and an actuator member connected with said ejecting means and projecting outwardly through said cover plate for manipulation to effect such displacement of the ejecting means.

4. In a vending machine having a hollow base unit having a side wall opening, a superposed compartment for articles to be dispensed by the machine, and a standard mounted upright in said base unit to provide support for said compartment; a unitary sub-structure comprising a cover plate for said side wall opening and having an article discharge passage communicating with the interior of said base unit through said side wall opening when the cover plate is in closing relation with said opening, feeding apron means for said discharge passage and carriage rail means both upon the inner side of said cover plate, said carriage rail means being connectible with said standard as a brace therefor when the cover plate is in closing relation with said opening, article ejecting means reciprocally mounted upon said rail means, means yieldably urging said article ejecting means into one limit of its reciprocal field, and an actuator member operably associated with said ejecting means and projecting outwardly through said cover plate for manipulation to displace the article ejecting means toward the other limit of its reciprocal field.

5. In a vending machine having a hollow base unit having a side wall opening, a superposed compartment for articles to be dispensed by the machine, and a standard mounted upright in said base unit to provide support for said compartment; a unitary sub-structure comprising a cover

plate for said side wall opening and having an article discharge passage communicating with the interior of said base unit through said side wall opening when the cover plate is in closing relation with said opening, carriage rail means upon the inner side of said cover plate connectible with said standard for bracing such rail means and said standard when the cover member is in the aforesaid closing relation, article ejecting means reciprocally mounted upon said rail means, means yieldably urging said article ejecting means into one limit of its reciprocal field, an actuator member operably associated with said ejecting means for manipulation to displace the same toward its opposite reciprocal limit and extending outwardly through the cover plate for accessibility, latch means operable to retain said ejecting means at the one reciprocal limit, and coin-controlled means mounted on said cover plate and operable to unlatch said latch means to free the ejecting means for displacement by said actuator member.

6. In a vending machine of the type having a multi-magazine turret rotatable to place selected of its magazines in registry with a discharge portion of the machine; the combination of a hollow base unit including bottom and side walls of sheet material the side wall being provided with an opening at said discharge portion, a standard mounted upright in said base unit on said bottom wall, turret bearing means on said standard for the support of said turret, and a unitary sub-structure comprising a cover plate for said side wall opening having a discharge passage communicating with the side wall opening, a feeding apron for said passage projecting therefrom upwardly and inwardly of said base unit, and extension means on said apron connected with said standard at a portion spaced upwardly from the base unit bottom wall for the mutual bracing of said standard and of said unitary sub-structure.
